UNITED STATES PATENT OFFICE.

JOHN H. MITCHELL, OF WASHINGTON, DISTRICT OF COLUMBIA, ASSIGNOR OF ONE-HALF TO MARY K. EMERY, MARY A. EMERY, AND WILLIAM VAN ZANDT COX, EXECUTORS AND TRUSTEES OF MATTHEW G. EMERY, DECEASED.

ANTISLIPPING HOOF-PAD.

SPECIFICATION forming part of Letters Patent No. 700,149, dated May 13, 1902.

Application filed September 26, 1901. Serial No. 78,626. (No model.)

To all whom it may concern:

Be it known that I, JOHN H. MITCHELL, a citizen of the United States, residing at Washington, in the District of Columbia, have invented a certain new and useful Antislipping Hoof-Pad, of which the following is a specification, reference being had therein to the accompanying drawings.

This invention relates to antislipping hoof-pads, the object in view being to provide a pad which may be removably applied to a horseshoe without detaching the shoe from the hoof.

The pad is designed for use as an emergency-pad and is so constructed that by carrying a set of pads in the vehicle to which the horse is hitched said pads may be applied readily and quickly to the shoes and hoofs while on the road, thus doing away with the necessity of driving the animal over a slippery surface to a shop where the shoes may be roughened in the usual way.

With the above general objects in view the invention consists in an antislipping hoof-pad embodying certain novel features and details of construction and arrangement of parts, as hereinafter fully described, illustrated, and claimed.

In the accompanying drawings, Figure 1 is a bottom perspective view of a hoof, showing the shoe and the improved pad applied thereto. Fig. 2 is an enlarged detail perspective view of the pad looking toward the upper side thereof. Fig. 3 is a vertical longitudinal section through the pad, indicating by dotted lines the relation of the pad to the shoe when in position.

Similar numerals of reference designate corresponding parts in all the figures.

Referring to the drawings, 1 designates an ordinary horseshoe, and 2 the body of the improved pad, said pad being shown applied to the shoe in Fig. 1. The body of the pad is preferably composed of felt or felted material, as shown, and to one side of the pad, or, in other words, the upper side of the pad when in place, there is applied a pair of keepers 3. The keepers are somewhat wedge-shaped in plan view, the inner adjacent

edges of the keepers being essentially inclined 50 with respect to each other, so as to diverge rearwardly and accommodate between them the frog of the hoof, as shown in Fig. 1.

The keepers 3, which are of leather or similar material, are secured to the upper surface of the pad by means of fasteners 4, preferably in the form of metallic staples, the same being driven through the keepers from the upper side and thence through the pad, where they are clenched securely against the 60 bottom of the body 2 of the pad, as shown in Fig. 3. Preparatory to fastening the keepers in place, however, a retaining-spring 5 is interposed between the keepers and the pad, said spring being held rigidly in place by 65 means of the same fasteners 4 which connect the keepers to the pad-body. By preference certain of the fasteners are driven through the keepers and pad, so as to embrace the end portions of the retaining-spring 5. The 70 spring 5 consists of a single flat strip of spring material of sufficient length to cause the extremities thereof to project beyond the ends of the pad far enough to allow the extremities of the spring to pass over the top of the shoe 75 1, between the shoe and the hoof, as indicated in Fig. 3, thus retaining the pad in place.

In order to cover the clenched ends of the fasteners, facing-strips 6, of leather or similar material, are placed over the end portions of 80 the bottom surface of the body of the pad, as illustrated, and said facing-strips are held in place by stitching the same to the body of the pad, as indicated at 7.

In placing the pad in position the pad is 85 given a partial twist, so as to extend obliquely across the shoe. This enables the extremities of the springs to be introduced between the shoe and hoof, and thereafter the pad is partially turned so as to enable 90 the spring to extend in a line transversely of the shoe and hoof. In this position the ends of the pad abut against the inner edges of the shoe, while the extremities 95 position themselves on opposite sides of the frog. The pad is therefore securely interlocked with the shoe and frog and accidental displacement of the pad prevented. A set of

pads may be readily carried in the vehicle or in a satchel and may be quickly applied whenever needed and removed when the occasion for their use is at an end.

5 Having thus described the invention, I claim as new—

1. An antislipping hoof-pad, comprising a felted oblong body, keepers fastened to the upper surface of the pad and having rearwardly-diverging adjacent edges, and a retaining-spring fastened between the keepers and body of the pad with its extremities projecting beyond the ends of the pad, said spring allowing the pad to project below the 15 horseshoe, substantially as and for the purpose specified.

2. An antislipping hoof-pad, comprising a felted body, keepers applied to the upper surface of the body of the pad, a retaining-spring interposed between the keepers and pad and arranged to permit the pad to project below the horseshoe, and fasteners passing through the keepers and pad and serving

to secure the keepers to the pad and also serving to secure the spring between the 25 keepers and pad.

3. An antislipping hoof-pad, comprising a felted body, keepers applied to the upper surface thereof, a retaining-spring held between the keepers and pad and arranged to 30 permit the pad to project below the horseshoe, fasteners which serve to secure the keepers to the pad and hold the spring between the keepers and pad, said fasteners being inserted through the keepers and pad and 35 clenched against the bottom of the pad, and facing-strips connected to the bottom of the pad and covering the clenched portions of the fasteners.

In testimony whereof I affix my signature 40 in presence of two witnesses.

JOHN H. MITCHELL.
